UNITED STATES PATENT OFFICE.

JOHN J. GAYNOR, OF INDIANAPOLIS, INDIANA.

BOTTLE-LABELING MACHINE.

1,197,477.

Specification of Letters Patent.

Patented Sept. 5, 1916.

Application filed May 19, 1916. Serial No. 98,661.

To all whom it may concern:

Be it known that I, JOHN J. GAYNOR, citizen of the United States, residing at Indianapolis, in the county of Marion and

5 State of Indiana, have invented certain new and useful Improvements in Bottle-Labeling Machines; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to labeling machines for bottles and the like and has for its object to provide improvements in machines of this class in the following particulars. First, in the construction and arrangement of the label picking and carrying mechanism. Second, in the arrangement for moving the conveyer intermittently conveying the bottles or the like to be 20 labeled to the labeling mechanism. Third in the construction and arrangement of the parts for delivering the bottles or the like from the conveyer to the labeling mechanism in a transverse direction. Fourth in the 25 construction and arrangement of the label affixing fingers. Fifth in the arrangement of the parts for delivering the bottles or the like from the labeling mechanism. Sixth in the construction and arrangement 30 of the parts which insures a perfect application of paste to the label carriers. Seventh in the construction and arrangement of the parts which insures a uniform position of the labels on the label carriers and 35 uniform positioning of the labels on the bottles or the like.

The invention consists in the novel construction of the label picking and carrying mechanism, and in the construction which 40 provides for the movement of the label carrying mechanism to the label box in a straight line.

The invention further consists in the construction and arrangement of the parts for 45 intermittently rotating the label picking and carrying mechanism.

The invention further consists in the novel construction and arrangement of the parts for holding and positioning the bottles or 50 the like to receive their labels.

The invention further consists in the ar-

rangement and construction of the label affixing fingers and for delivering the labeled bottles from the labeling mechanism. 60

The invention further consists in the novel construction for intermittently moving the bottle conveyer and in the construction and arrangement of the parts for delivering the bottles from the conveyer to 65 the labeling mechanism.

The invention further consists in certain other novel details of construction and in combinations of parts, all of which will be first fully described and afterward specifically pointed out in the appended claims. 70

Referring to the accompanying drawings: Figure 1 is a side elevation partly in section of a labeling machine constructed in accordance with this invention, and illustrating the 75 label picking and carrying mechanism in the position of picking a label or labels from the label box. Fig. 2 is a similar view illustrating the label picking and carrying mechanism with label thereon. Fig. 3 is a similar view illustrating the label picker and carrier as being rotated to carry its label into position to be applied to a bottle. Fig. 4 is a similar view illustrating the label picker and carrier as having been rotated 80 and with its label or labels in proper position to be affixed to a bottle. Fig. 5 is a similar view illustrating the label picker and carrier as having received a bottle to 85 which the label or labels are to be affixed. Fig. 6 is a similar view illustrating the label affixing fingers in the act of affixing the label or labels to a bottle. Fig. 7 is a front elevation illustrating the parts in position shown in Fig. 6, and also illustrating 90 in dotted lines the label affixing fingers and bottle in position of being delivered from the labeling mechanism. Fig. 8 is a top plan view with label box removed illustrating a bottle in broken lines on the conveyer and 95 in dotted lines as having been delivered therefrom transversely of the conveyer into the label carrier. Fig. 9 is a side elevation with the conveyer removed illustrating the label picker and carrier and label wipers as 100 moving upwardly toward the label box, the labels having been stripped from the label carrier by this upward movement and the label wipers shown in the act of wiping the labels on the bottle. Fig. 10 is a fragmentary detail view of one pair of label pickers and carriers. Fig. 11 is a vertical trans-

105

110

verse sectional view through the bottle conveyer driving sprocket drum illustrating the sprocket in elevation and the mechanism for causing an intermittent rotation of the 5 conveyer driving shaft. Fig. 12 is a fragmentary elevation partly in section illustrating the conveyer driving sprocket, its drum and ratchet and pawl for causing an intermittent rotation of the conveyer driving shaft. Fig. 13 is an enlarged fragmentary sectional view through the label picker and carrier shaft taken on line 13—13 of Fig. 7, and illustrating the drum for rotating said shaft and the label picker and 10 carrier. Fig. 14 is an enlarged fragmentary sectional view through the same taken on line 14—14 of Fig. 7, and illustrating the ratchet and pawl mechanism therein for rotating the label picker and carrier shaft in 15 one direction. Fig. 15 is an enlarged transverse sectional view through the drum for rotating the label picker and carrier and its shaft and Fig. 16 is a fragmentary sectional view through the pivot or hinge of the arm carrying the label affixing fingers.

Like numerals of reference indicate the same parts throughout the several figures.

In using the word bottle in the following specification and claims it is to be understood I refer also to cans or other like articles to which a label or labels are applied, as it is obvious that this machine is capable of simple modification for the labeling of cans and the like.

Referring to the accompanying drawings by reference numerals; 1 indicates the machine having suitable frame-work 2, and 3 indicates a vertically slidable shaft upon which the label picking and carrying mechanism 4 are mounted, the frame 2 being provided at its top and bottom with bearings 5 and 6 which in turn are each provided with gib (not shown) entering the vertical slots 7 and 8 in the slidable shaft 3 so as to permit a free sliding movement to said shaft but which prevent any rotary movement thereof.

Secured to the shaft 3 as shown in Fig. 8 is a bracket 9 having two downwardly depending vertical arms 10 which form journals 11 and 12 for the horizontal shaft 13 upon which the label picking and carrying mechanism 4 is mounted and rotatable therewith. The label picking and carrying mechanism includes a substantially flat rectangular member 14 from each corner of which extends horizontally the bases or supports 15 for the label picking and carrying fingers 16 (Fig. 9), said fingers 16 being arranged in two pairs as shown and hinged at 17 to the supports 15. From Fig. 10 it will be seen that a leaf spring 18 holds each finger 16 in its normal closed position, while a small spiral spring 19 seated in each support 15 lends flexibility to each finger 16 so

that the fingers can assume the position shown in dotted lines in Fig. 10. The purpose of this construction is that when the said fingers come into contact and pass over the paste feed roll which will be presently described, they will the more perfectly conform to the paste feed roll so as to insure an even distribution of paste upon the surfaces of the fingers. Secured also to the slidable shaft 3 as shown in Figs. 7 and 8 is a bifurcated bracket 20 to which the body and neck label wipers 21 and 22 are secured, said wipers being positioned directly under the label carriers 16 as shown in Fig. 9.

Pivoted at 23 (Fig. 7) is the arm 24 carrying the label affixing fingers 25 and 26, which fingers include stems 27 mounted in guides 28 formed in the arm 24, the said stems 27 being each provided with a head 29 for direct engagement with labels and conforming to the contour of the bottles. A spiral spring 30 is also provided on the stems 27 to hold the same in their normal extended position and to impart the necessary resiliency to the fingers.

31 indicates the conveyers for conveying the bottles to the labeling mechanism and includes two endless sprocket chains 32 and 33 connected together by blocks 34 forward and spaced apart to receive bottles to be 95 labeled. The said chains pass over sprockets 35 at the formed end of the machine, and pass over driving sprockets 36 about centrally of the machine and mounted on a driving shaft 37. By means of this conveyer, bottles are carried into position of the bottle shown in Fig. 8, by an intermittent movement of the conveyer as will be now described.

Referring to Figs. 8, 11 and 12, 38 indicates a driving sprocket loosely mounted on the conveyer driving shaft 37, said sprocket 38 being in close association with a hollow drum 39 fixed to the frame-work of the machine as by an arm 40, the said shaft 37 passing freely through said drum in the manner as shown in Fig. 12. The internal surface of the drum 39 provides a cam 40 as shown in Fig. 11 which it will be understood is stationary relative to the shaft 37 and its 115 loosely mounted driving sprocket 38. Upon the face of the sprocket 38 and adjacent the drum 39 is pivoted a pawl 41 which extends within the hollow drum 39 and which is provided with a roller 42 held in rolling 120 contact with the internal cam surface 40 of the drum 39 by means of a leaf spring 43. Keyed to the conveyer driving shaft 37 is a ratchet wheel 44 to be engaged by the pawl 41, said ratchet being preferably provided 125 with four teeth as shown. Upon rotation of the sprocket 38 the pawl 41 thereon engages a tooth in the ratchet wheel 44 as shown in full lines in Fig. 11, communicating its rotary movement to the conveyer drive shaft 130

37 to move the conveyer 31. When however the pawl 41 reaches the position shown in dotted lines in Fig. 11 which is the distance between two teeth on the ratchet, the roller 42 5 engages the cam surface 40 in the drum 39 which swings the pawl 41 out of engagement with the ratchet 44, thus releasing the sprocket 38 from all driving connection with the shaft 37, so that said shaft and the 10 conveyer 31 comes to a full stop and remain stopped until the pawl 41 again reaches the position shown in full lines in Fig. 11 at which point the roller 42 passes off of the cam 40 and allows the pawl to drop into a 15 tooth in the ratchet to again rotate the shaft 37 and move the conveyer 31. This movement of the conveyer is just the distance between two bottles thereon, and is only sufficient to bring the bottles successively into 20 position shown in broken lines in Fig. 8, at which position the movement of the conveyer ceases so that the bottle may be delivered from the conveyer into position shown in dotted lines in Fig. 8, which is accomplished in the following manner.

As heretofore described, the label picking and carrying mechanism includes the substantially rectangular plate 14, the finger supporting arms 15 and the hinged label picking and carrying fingers 16, thus leaving the interior open. When therefore this mechanism is in position shown in Fig. 4, the bottle on the conveyer shown in broken lines in Fig. 8 is directly opposite the mechanism 4 and slightly above the inner concaved surfaces of the lowermost pair of fingers 16, the position of the said bottle on the conveyer being as indicated at A in Fig. 4. The conveyer 31 being in close association 30 with the mechanism 4, and while the conveyer is at rest, the bottle delivering arm 45 (Fig. 8) in engagement with the cap end of the bottle, is swung on its pivot 46 into position shown in dotted lines in Fig. 8, 35 which delivers the bottle transversely from the conveyer into position shown in dotted lines in Fig. 8 which is the position shown in full lines in Fig. 5. The bottle thus enters the label picking and carrying mechanism 4, 40 and rests upon the lowermost pair of fingers 16 as shown in Fig. 5, and is positioned under the horizontal stationary bottle holding arm 47 shown in dotted lines in Fig. 5 and in full lines in Fig. 7, said arm 47 being 45 suitably fixed to the frame-work and substantially V shaped in cross section so as to provide for efficient engagement with the bottle.

The movement of the bottle delivering 50 arm 45 is accomplished in the following manner: The arm 45 being pivoted at 46 (Fig. 8) to a bracket 48 fixed to the frame of the machine is provided with a short horizontally extending arm 49 angularly disposed with relation to the arm 45, said short

arm 49 being positioned close to and in the path of rotation of an arm 50 mounted on and rotatable with the main drive shaft 51 which is mounted transversely of the machine in journals 52 and 53. Said drive shaft 51 is driven in any suitable manner as by a belt pulley 54 and at every revolution of the shaft 51, the arm 50 thereon strikes the short arm 49 on the bottle delivering arm 45, moving said arm 45 from position shown in full lines in Fig. 8 to position shown in dotted lines in said figure, thus delivering a bottle from the conveyer 31 into position shown in dotted lines in said figure as has been previously described, a coil spring 55 connected from the frame-work to the arm 45 returns said arm to its normal position as shown in Fig. 8.

The movement of the label picking and carrying mechanism will now be described. As heretofore stated the label picking and carrying mechanism 4 is fast on the shaft 13 and is revoluble therewith, while said shaft 13 is journaled in the arms 10 of the bracket 9, which bracket is mounted on the vertical 50 slidable shaft 3. Connected to said shaft 3 at 56 (Fig. 2) is a link 57 which in turn is pivoted at 58 to a lever 59 pivoted on a transverse shaft 60, said lever 59 being shaped as shown in Fig. 2 with its intermediate portion 61 substantially horizontal. Mounted on the drive shaft 51 is a crank 62 carrying a roller 63 for engagement with the lower edge of the portion 61 of the lever 59. Upon rotation of the drive shaft 51 and crank 62 counter-clockwise the roller 63 engages the lever 59 as shown in Fig. 6, and raises said lever into position shown in Fig. 1. This movement of the lever 59 is communicated to the vertical slidable shaft 3 and raises the 55 same and the label picking and carrying mechanism into position shown in Fig. 1, in which position the label picking fingers having paste thereon as will be presently described, picks a label or labels from the label box or boxes 64 mounted at the top of the machine and in line of the vertical movement of the label picking and carrying mechanism 4. As the roller 63 passes out of contact with the lever 59 and into position 60 shown in Fig. 2, the label picking and carrying mechanism 4 with label or labels thereon, moves vertically down into position shown in Fig. 2. It will be noted from Fig. 2 that the label 65 is in its uppermost position on 65 the fingers 16.

The next operation is to rotate the mechanism 4 to bring the same into position to receive a bottle and to have its label applied thereto. In this connection reference is 70 made to Fig. 3 and also to Fig. 2. From the latter figure it will be seen that a lever 66 is pivoted at 67 to the vertical shaft 3 (Fig. 8), and from Fig. 2 it will be seen that the drive shaft 51 is provided with a crank 75

68 carrying a roller 69, the rear rounded end of the lever 66 being in the path of rotation of the roller 69, while the front end 70 is connected to a strap 71 fixed to the periphery of the drum 72.

Referring to Figs. 13, 14 and 15 it will be seen that the drum 72 is provided with a peripheral groove 73 to receive the strap 71, said drum being loosely mounted on the shaft 13 which carries the label picking and carrying mechanism 4. The drum 72 is provided with a central thin web 74 forming two chambers 75 and 76 with respect to the rim of the drum. Pivoted to this central web 74 (Fig. 14) is a pawl 77 and a leaf spring 78, while keyed to the shaft 13 is a two toothed ratchet wheel 79. On the opposite or inner side of the central web 74 (Fig. 13 and Fig. 15) fastened thereto at 80 is a coil spring 81 having several turns about the shaft 13 and having its other or inner end secured at 82 to the inner arm 10 of the bracket 9. Projecting from said arm 10 and within the chamber 75 of the drum 72 is 25 a stop 83 (Figs. 13 and 15), and extending from the rim of the drum 73 is a stop 84 (Figs. 13 and 15), by means of which stops the movement of the drum 72 on the shaft 13 is limited, it being understood that the 30 tension or strain of the spring 81 is in the direction to hold said stops in engagement as shown in Fig. 13. When these two stops are in position shown in Fig. 13, the pawl 77 (Fig. 14) in the drum 72 is in position 35 shown in Fig. 14 and in engagement with one of the two teeth of the ratchet wheel 79. When therefore the lever 66 (Fig. 2) is engaged by the roller 69 on the crank 68 and is carried into position shown in Fig. 3, the 40 end 70 of said lever is depressed and carries the strap 71 with it, thus unwinding the strap from the drum 72 which rotates said drum which movement is communicated to the shaft 13 by means of the pawl 78 and ratchet 79. As the mechanism 4 is fixed to the shaft 13 it is rotated through the position shown in Fig. 3 and into position shown 45 in Fig. 4, in which position the lever 66 is released by the roller 69. The coil spring 81 within the drum 72 then rotates the drum 72 in the reverse direction, again bringing the stops 83 and 84 into position shown in Fig. 13, and carrying the pawl 77 into its first position and into engagement with the 50 other of the two teeth in the ratchet 79 as shown in Fig. 14. This reverse rotation of a half revolution of the drum 72 again winds the strap 71 thereon and brings the lever 66 back to its normal position as shown in Fig. 52. When the label carrying mechanism 4 has thus been rotated a half revolution from the position shown in Fig. 2 to that shown in Fig. 4, the label 65 is in its lowermost 60 position on the fingers 16 and is in position to be affixed to a bottle. When the parts are 65

in this position, the conveyer 31 is so timed as to have brought a bottle into position shown in broken lines in Fig. 8, and when the labeling mechanism is in position shown in Fig. 4, the conveyer movement mechanism 70 heretofore described is in position shown in dotted lines in Fig. 11. The conveyer therefore is at rest, and the arm 50 (Fig. 8) is so timed as to engage the arm 49 of the pivoted bottle delivery arm 45 to move the arm 45 75 into position shown in dotted lines in Fig. 8, thus delivering the bottle transversely of the conveyer into position shown in dotted lines in Fig. 8, and within the labeling mechanism 4 as shown in Fig. 5. When the bottle is thus in position shown in dotted lines in Fig. 8 and in full lines in Fig. 5 the same is in proper position relatively to the label or labels in the fingers 16 to receive said label or labels, and the application of the 80 label or labels to the bottle is accomplished in the following manner: The arm 24 (Fig. 7) carrying the label affixing fingers 25 and 26 heretofore described is pivoted at 23, said arm having a boss 24¹ adjacent the pivot 23 90 (Fig. 16) to which is pivotally connected the swivel 25¹, said swivel 25¹ being provided with a stud 26¹ entering a socket in the boss 24¹, said swivel 25¹ being also provided with a transverse hole 25² to receive the end of 95 the lever 30¹, (Figs. 6, 7, and 8.) The lever 30¹ is pivoted on the shaft 60 and is shaped as shown in Fig. 9. Mounted on the lever 30¹ about centrally thereof is a roller 30² shown in dotted lines in Fig. 9 and in side 100 elevation in Fig. 7. Mounted on the drive shaft 51 and rotatable therewith is a cam 35¹ (Figs. 7, 8 and 4) which engages the roller 30² on the lever 30¹ to raise said lever 30¹ from position shown in Fig. 5 to position 105 shown in Fig. 6. This upward movement of the lever 30¹ carries the arm 24 of the label affixing fingers 25 and 26, from the position shown in dotted lines in Fig. 7 into position shown in full lines in said figure, which is 110 also the position shown in full lines in Fig. 6. This upward movement of the label affixing fingers 25 and 26 carries the label or labels into contact with the bottle as shown in Fig. 6 and raises the bottle off of the fingers 16 into engagement with the horizontal bottle holding arm 47 (Figs. 6 and 7). As this movement of the label affixing finger is accomplished the arm 59 is raised by the roller 69 which lifts the vertical shaft 3 and the label carrying device 4 into position 115 shown in Fig. 9. During this movement the cam 35¹ continues in engagement with the roller 30² which holds the label affixing finger 25 and 26 in close contact with the bottle and holds the bottle tightly between said finger and the bottle holding arm 47. 120

As the label carrying device 4 moves upwardly into position shown in Fig. 9 under the influence of the lever 59, the label wipers 130

21 and 22 which are connected to the slide-
able shaft 3 move upwardly therewith while
the bottle is being held stationary and
against movement. This upward movement
5 of the label carrying device 4 causes the
label carrying fingers 16 to open on their
hinges 17 (Fig. 9) to allow same to pass over
the bottle, thus stripping the label or labels
10 from the fingers 16 and leaving the label or
labels held against the bottle by the affixing
fingers 25 and 26. The label wipers 21 and
22 follow directly under the fingers 16, and
as they continue on their upward movement,
15 said wipers engage the labels and wipe the
same on the bottle. It will be noted that the
bottle wipers 21 and 22 pass over the labels
in a straight line and while the bottle is
held stationary thus insuring a perfect wip-
ing and smoothing out of the labels.
20 As soon as the label wipers have passed
off of the labels, the cam 35' passes from
under the roller 30", thus allowing the arm
30' to swing downwardly on its pivot which
causes the label affixing finger arm 24 to
25 drop on its pivot into position shown in
dotted lines in Fig. 7. The bottle follows
the movement of the affixing fingers 25 and
26 and into position shown in dotted lines
in Fig. 7 from which position it drops by
30 gravity in the direction of the arrow on the
conveyer apron 50', a guiding member 50"
being provided adjacent the apron 50' to in-
sure delivery of the bottle on the apron in
an upright or upstanding position. This
35 conveyer 50' (Fig. 6) passes over a drum
55' on a shaft 55" and over a drum 56' on
a shaft 56" driven by a sprocket 57' to con-
vey the bottles with labels thereon rear-
wardly of the machine.
40 Referring now to the paste applying de-
vice 60' (Figs. 3 and 8), it will be seen that
the same includes a paste box 60" to contain
paste and a paste feed roll 62' driven by a
pulley 62" belted from the drive shaft 51
45 (Fig. 8), said feed roll 62' being in rolling
contact with the paste distributing roll 63'
which is located in the path of rotation of
the label picking and carrying fingers 16.
As the label carrying device 4 rotates from
50 position shown in Fig. 2 through position
shown in Fig. 3 and into position shown in
Fig. 4, the label picking and carrying fin-
gers 16 (Fig. 3) pass successively over the
paste distributing roll 63' to receive a suit-
55 able supply of paste therefrom. As the fin-
gers 16 engage and pass over the distribut-
ing roll 63', said fingers conform to the roll
to insure an even distribution of paste
thereon by means of the arrangement shown
60 in Fig. 10.
Having thus fully described the several
parts of the invention, its operation is as
follows: We will consider the position of the
parts as shown in Fig. 1 as being the first
65 position. In this position the label picking
and carrying device is shown in its upper-
most position and in the act of picking a
label or labels from the label box. The label
picking and carrying device with a label or
labels under influence of its operating mech-
anism moves downwardly in a vertical di-
rection into position shown in Fig. 2. The
label picking and carrying device 4 is then
rotated through position shown in Fig. 3,
during which one pair of fingers 16 receive
70 a supply of paste, and assumes the position
shown in Fig. 4. This movement is accom-
plished by means of the mechanism hereto-
fore described and carries the label into po-
sition to be affixed to a bottle. At the time
75 80 the label carrying device is in position shown
in Fig. 4, the bottle to be labeled is in posi-
tion on the conveyer 31 as shown in broken
lines in Fig. 8, and the movement of the con-
veyer is stopped by the mechanism hereto-
fore described and shown in detail in Figs.
85 90 11 and 12. The bottle is then delivered
transversely of the conveyer 31 by the arm
45 (Fig. 8) into position shown in dotted
lines in said figure and in full lines in Fig. 5.
The label fingers 25 and 26 are then raised
from position shown in dotted lines in Fig.
7 to full lines in Fig. 6 which carries the
label or labels into contact with the bottle
within the label carrying device 4, and
95 100 105 clamps the bottle between said fingers and
the horizontal bottle holding arm 47. When
the parts are in this position, the label car-
rying device 4 moves upwardly into position
shown in Fig. 9, which movement strips the
label or labels from the fingers 16 and wipes
the label or labels on the bottle. The label
picking and carrying device continues its
upward movement in a straight line to the
label box into position shown in Fig. 1, and
110 115 120 the bottle with label or labels thereon drops
into position shown in dotted lines in Fig.
7 and is delivered to the delivering conveyer
50' in an upright or upstanding position.
It is of course apparent that this inven-
tion is susceptible to various changes in the
construction and arrangement of the parts,
and the accompanying drawings simply
show one embodiment thereof. I do not
consider myself limited in any way to the
exact construction shown and described but
consider myself clearly entitled to all such
changes and variations as fall within the
limit and scope of the appended claims.
What I claim as new and desire to secure
by Letters Patent of the United States is—
1. A bottle labeling machine including an
intermittently rotatable and vertically mov-
able label picking and carrying device, a
label box disposed in the path of movement
of said label picking and carrying device,
an intermittently movable bottle conveyer
for conveying bottles to be labeled, means
for delivering a bottle in a transverse direc-
tion from the said conveyer into the said

label picking and carrying device, label affixing fingers, means for moving the same into engagement with a label on said label picking and carrying device to affix a label to a bottle, label wipers vertically movable with said label picking and carrying device, means for moving said label picking and carrying device and said bottle wipers to strip a label from the label picking and carrying device and wipe same on a bottle, means for delivering a bottle in an upright position and means for conveying the labeled bottles.

2. A bottle labeling machine including an intermittently rotatable and vertically movable label picking and carrying device, a label box disposed in the path of movement of said label picking and carrying device, an intermittently movable bottle conveyer for conveying bottles to be labeled, means for delivering a bottle in a transverse direction from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said label wipers to strip a label from the label picking and carrying device and wipe same on a bottle and means for delivering a bottle in an upright position.

Right position.

3. A bottle labeling machine including an intermittently rotatable and vertically movable label picking and carrying device, a label box disposed in the path of movement of said label picking and carrying device, an intermittently movable bottle conveyer for conveying bottles to be labeled, means for delivering a bottle in a transverse direction from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle.

4. A bottle labeling machine including an
intermittently rotatable and vertically mov-
able label picking and carrying device, a
label box disposed in the path of movement
of said label picking and carrying device, a
movable bottle conveyer for conveying bot-
tles to be labeled, means for delivering a

bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said bottle wipers to strip a label from said label picking and carrying device and wipe same on a bottle, means for delivering a bottle in an upright position and means for conveying the labeled bottles. 70 75 80

5. A bottle labeling machine including an intermittently rotatable and vertically movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said label wipers to strip a label from the label picking and carrying device and wipe same on a bottle and means for delivering a bottle in an upright position. 85 90 95 100

6. A bottle labeling machine including an intermittently rotatable and vertically movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle. 125

7. A bottle labeling machine including a rotatable and vertically movable label picking and carrying device, a label box disposed in the path of movement of said label picking and carrying device, an inter- 130

mittently movable bottle conveyer for conveying bottles to be labeled, means for delivering a bottle in a transverse direction from the said conveyer into the said label 5 picking and carrying device, label affixing fingers, means for moving the same into engagement with a label on said label picking and carrying device to affix a label to a bottle, label wipers vertically movable with 10 said label picking and carrying device, means for moving said label picking and carrying device and said bottle wipers to strip a label from the label picking and carrying device and wipe same on a bottle, 15 means for delivering a bottle in an upright position and means for conveying the labeled bottles.

8. A bottle labeling machine including a rotatable and vertically movable label picking and carrying device, a label box disposed in the path of movement of said label picking and carrying device, an intermittently movable bottle conveyer for conveying bottles to be labeled, means for delivering a bottle in a transverse direction from the said conveyer into the said label picking and carrying device, label affixing fingers, means for moving the same into engagement with a label on said label picking 25 and carrying device to affix a label to a bottle, label wipers vertically movable with said label picking and carrying device, means for holding a bottle stationary with respect to said label picking and carrying device, means for moving said label picking and carrying device and said wipers to strip a label from the label picking and carrying device and wipe same on a bottle and means for delivering a bottle in an upright position. 30

9. A bottle labeling machine including a rotatable and vertically movable label picking and carrying device, a label box disposed in the path of movement of said label picking and carrying device, an intermittently movable bottle conveyer for conveying bottles to be labeled, means for delivering a bottle in a transverse direction from the said conveyer into the said label picking and carrying device, label affixing fingers, means for moving the same into engagement with a label on said label picking and carrying device to affix a label to a bottle, label wipers vertically movable with 45 said label picking and carrying device, means for holding a bottle stationary with respect to said label picking and carrying device, and means for moving said label picking and carrying device and said bottle wipers to strip a label from the label picking and carrying device and wipe same on a bottle. 50

10. A bottle labeling machine including a rotatable and vertically movable label picking and carrying device, a label box disposed

in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said bottle wipers to strip a label from said label picking and carrying device and wipe same on a bottle, means for delivering a bottle in an upright position and means for conveying the labeled bottles. 70

11. A bottle labeling machine including a rotatable and vertically movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said bottle wipers to strip a label from the label picking and carrying device and wipe same on a bottle and means for delivering a bottle in an upright position. 80

12. A bottle labeling machine including a rotatable and vertically movable label picking and carrying device, a label box disposed in the path of movement of said label picking and carrying device, a movable bottle conveyer for carrying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle. 90

13. A bottle labeling machine including an intermittently rotatable and reciprocating movable label picking and carrying device, a label box disposed in the path of 105

ing device, an intermittently movable conveyer for conveying bottles to be labeled, means for delivering a bottle in a transverse direction from the said conveyer into the said label picking and carrying device, label affixing fingers, means for moving the same into engagement with a label on said label picking and carrying device to affix a label to a bottle, label wipers vertically movable with said label picking and carrying device, means for moving said label picking and carrying device and said bottle wipers to strip a label from the label picking and carrying device and wipe same on a bottle, means for delivering a bottle in an upright position and means for conveying the labeled bottles.

26. A bottle labeling machine including
a movable label picking and carrying de-
vice, a label box disposed in the path of
movement of said label picking and carry-
ing device, an intermittently movable bot-
tle conveyer for conveying bottles to be la-
beled, means for delivering a bottle in a
25 transverse direction from the said conveyer
into the said label picking and carrying
device, label affixing fingers, means for mov-
ing the same into engagement with a label
on said label picking and carrying device
30 to affix a label to a bottle, label wipers ver-
tically movable with said label picking and
carrying device, means for holding a bottle
stationary with respect to said label picking
and carrying device, means for moving said
35 label picking and carrying device and said
label wipers to strip a label from the label
picking and carrying device and wipe same
on a bottle and means for delivering a bot-
tle in an upright position.

40 27. A bottle labeling machine including a
movable label picking and carrying device,
a label box disposed in the path of move-
ment of said label picking and carrying de-
vice, an intermittently movable bottle con-
veyer for conveying bottles to be labeled,
means for delivering a bottle in a transverse
direction from the said conveyer into the
said label picking and carrying device, label
affixing fingers, means for moving the same
50 into engagement with a label on said label
picking and carrying device to affix a label
to a bottle, label wipers vertically movable
with said label picking and carrying de-
vice, means for holding a bottle stationary
55 with respect to said label picking and carry-
ing device, and means for moving said label
picking and carrying device and said bottle
wipers to strip a label from the label pick-
ing and carrying device and wipe same on
60 a bottle.

28. A bottle labeling machine including a movable label picking and carrying device, a label box disposed in the path of movement of said label picking and carrying device, a movable bottle conveyer for

conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said bottle wipers to strip a label from said label picking and carrying device and wipe same on a bottle, means for delivering a bottle in an upright position and means for conveying the labeled bottles.

29. A bottle labeling machine including a movable label picking and carrying device, a label box disposed in the path of the movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said label wipers to strip a label from the label picking and carrying device and wipe same on a bottle and means for delivering a bottle in an upright position.

30. A bottle labeling machine including a movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle.

31. A bottle labeling machine including a movable label picking and carrying device, a label box disposed in the path of movement of said label picking and carrying device, an intermittently movable bottle conveyor for conveying bottles to be labeled, means for delivering a bottle in a transverse

- into engagement with a label on said label picking and carrying device to affix a label to a bottle, label wipers vertically movable with said label picking and carrying device, means for moving said label picking and carrying device and said bottle wipers to strip a label from the label picking and carrying device and wipe same on a bottle, means for delivering a bottle in an upright position and means for conveying the labeled bottles.

38. A bottle labeling machine including a
movable label picking and carrying device,
a label box disposed in the path of movement
15 of said label picking and carrying device,
an intermittently movable bottle conveyer
for conveying bottles to be labeled, means
for delivering a bottle in a transverse direc-
tion from the said conveyer into the said
20 label picking and carrying device, label af-
fixing fingers, means for moving the same
into engagement with a label on said label
picking and carrying device to affix a label
to a bottle, label wipers vertically movable
25 with said label picking and carrying device,
means for holding a bottle stationary with
respect to said label picking and carrying
device, means for moving said label pick-
ing and carrying device and said label wipers
30 to strip a label from the label picking and
carrying device and wipe same on a bottle
and means for delivering a bottle in an up-
right position.

Right position.

39. A bottle labeling machine including
35 a movable label picking and carrying de-
vice, a label box disposed in the path of
movement of said label picking and carry-
ing device, an intermittently movable bottle
conveyer for conveying bottles to be labeled,
40 means for delivering a bottle in a transverse
direction from the said conveyer into the
said label picking and carrying device, label
affixing fingers, means for moving the same
into engagement with a label on said label
45 picking and carrying device to affix a label
to a bottle, label wipers vertically movable
with said label picking and carrying device,
means for holding a bottle stationary with
respect to said label picking and carrying
50 device and said bottle wipers to strip a
label from the label picking and carrying
device and wipe same on a bottle.

55 40. A bottle labeling machine including a movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device,

means for holding a bottle stationary with respect to said label picking and carrying device, means for moving said label picking and carrying device and said bottle wipers to strip a label from said label picking and carrying device and wipe same on a bottle, means for delivering a bottle in an upright position and means for conveying the labeled bottles. 76

41. A bottle labeling machine including a movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said label wipers to strip a label from the label picking and carrying device and wipe same on a bottle and means for delivering a bottle in an upright position. 75

42. A bottle labeling machine including a movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle. 110 115 120 125 130 135 140 145 150 155 160 165 170 175 180 185 190 195 200

- carrying device and said bottle wipers to strip a label from the label picking and carrying device and wipe same on a bottle, means for delivering a bottle in an upright position and means for conveying the labeled bottles. 5
44. A bottle labeling machine including a movable label picking and carrying device, a label box disposed in the path of movement of said label picking and carrying device, an intermittently movable bottle conveyer for conveying bottles to be labeled, means for delivering a bottle in a transverse direction from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said wipers to strip a label from the label picking and carrying device and wipe same on a bottle and means for delivering a bottle in an upright position. 20
45. A bottle labeling machine including a movable label picking and carrying device, a label box disposed in the path of movement of said label picking and carrying device, an intermittently movable bottle conveyer for conveying bottles to be labeled, means for delivering a bottle in a transverse direction from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle. 45
46. A bottle labeling machine including a movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device, means for moving said label picking
- and carrying device and said bottle wipers to strip a label from said label picking and carrying device and wipe same on a bottle, means for delivering a bottle in an upright position and means for conveying the labeled bottles. 70
47. A bottle labeling machine including a movable label picking and carrying device, a label box disposed in the path of movement of said label picking and carrying device, a movable bottle conveyer for conveying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, means for moving said label picking and carrying device and said label wipers to strip a label from the label picking and carrying device and wipe same on a bottle and means for delivering a bottle in an upright position. 85
48. A bottle labeling machine including a movable label picking and carrying device, a label box disposed in the path of movement of said label picking and carrying device, a movable bottle conveyer for carrying bottles to be labeled, means for delivering a bottle from the said conveyer into the said label picking and carrying device, label affixing fingers, means for moving the same into engagement with a label on said label picking and carrying device to affix a label to a bottle, label wipers vertically movable with said label picking and carrying device, means for holding a bottle stationary with respect to said label picking and carrying device, and means for moving said label picking and carrying device and said bottle wipers to strip a label from the label picking and carrying device and wipe same on a bottle. 95
49. A bottle labeling machine including a label picking and carrying device, a label box, means for moving the label picking and carrying device to the label box vertically to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer intermittently to bring a bottle in position to be delivered to the label picking and carrying device, means for delivering a bottle transversely from the conveyer into said label picking and carrying device and adjacent a label thereon, a label affixing finger, means for moving the 115
- 120
- 125
- 130

said label picking and carrying device and said label wiper to move with respect to a bottle and to the label affixing finger to strip a label from the label picking and carrying device and wipe same on a bottle, and a conveyer for conveying a labeled bottle.

54. A bottle labeling machine including a label picking and carrying device, a label box, means for moving the label picking and carrying device to the label box vertically to pick a label therefrom, a paste supplying means, means for rotating said label picking and carrying device to gather a supply of paste from the paste supply means and to carry a label into position to be affixed to a bottle, a conveyer for conveying bottles to be labeled, means for moving said conveyer to bring a bottle in position to be delivered to the label picking and carrying device, means for delivering a bottle from the conveyer into said label picking and carrying device and adjacent a label thereon, a label affixing finger, means for moving the same into engagement with a label on the label picking and carrying device and to affix the same to a bottle thereon, a movable label wiper, means for coacting with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle.

55. A bottle labeling machine including a label picking and carrying device, a label box, means for moving the label picking and carrying device to the label box in a straight line to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer to bring a bottle in position to be delivered to the label picking and carrying device, means for delivering a bottle from the conveyer into said label picking and carrying device and adjacent a label thereon, a label affixing finger, means for moving the same into engagement with a label on the label picking and carrying device and to affix the same to a bottle thereon, a movable label wiper, means for coacting with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle.

bottle, and a conveyer for conveying a labeled bottle.

56. A bottle labeling machine including a label picking and carrying device, a label box, means for moving the label picking and carrying device to the label box in a straight line to pick a label therefrom, a paste supplying means, means for rotating said label picking and carrying device to gather a supply of paste from the paste supply means and to carry a label into position to be affixed to a bottle, a conveyer for conveying bottles to be labeled, means for moving said conveyer to bring a bottle in position to be delivered to the label picking and carrying device, means for delivering a bottle from the conveyer into said label picking and carrying device and adjacent a label thereon, a label affixing finger, means for moving the same into engagement with a label on the label picking and carrying device and to affix the same to a bottle thereon, a movable label wiper, means for co-acting with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle.

57. A bottle labeling machine including a label picking and carrying device, a label box, means for moving the label picking and carrying device to the label box to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer intermittently to bring a bottle in position to be delivered to the label picking and carrying device, means for delivering a bottle transversely from the conveyer into said label picking and carrying device and adjacent a label thereon, a label affixing finger, means for moving the same into engagement with a label on the label picking and carrying device and to affix the same to a bottle thereon, a movable label wiper, means co-acting with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle, and a conveyer for conveying a labeled bottle.

58. A bottle labeling machine including a label picking and carrying device, a label

box, means for moving the label picking and carrying device to the label box to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer intermittently to bring a bottle in position to be delivered to the label picking and carrying device, means for delivering a bottle transversely from the conveyer into said label picking and carrying device and adjacent 10 a label thereon, a label affixing finger, means for moving the same into engagement with a label on the label picking and carrying device and to affix the same to a bottle thereon, a movable label wiper, means for coating 15 with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle.

59. A bottle labeling machine including 30 a label picking and carrying device, a label box, means for moving the label picking and carrying device to the label box to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer intermittently to bring a bottle in position to be delivered to the label picking and carrying device, means for delivering a bottle transversely from the conveyer into said label picking and carrying device and adjacent 35 a label thereon, a label affixing finger, means for moving the same into engagement with a label on the label picking and carrying device and to affix the same to a bottle thereon, a movable label wiper, means for coating 40 with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle, and a conveyer for conveying a labeled bottle.

60. A bottle labeling machine including 45 a label picking and carrying device, a label box, means for moving the label picking and carrying device to the label box to pick a label therefrom, a paste supplying means, means for rotating said label picking and

carrying device to gather a supply of paste from the paste supply means and to carry a label into position to be affixed to a bottle, a conveyer for conveying bottles to be labeled, means for moving said conveyer intermittently to bring a bottle in position to be delivered to the label picking and carrying device, means for delivering a bottle transversely from the conveyer into said label picking and carrying device and adjacent 50 a label thereon, a label affixing finger, means for moving the same into engagement with a label on the label picking and carrying device and to affix the same to a bottle thereon, a movable label wiper, means for coating 55 with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle.

61. A bottle labeling machine including 60 a label picking and carrying device, a label box, means for moving the label picking and carrying device to the label box to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer to bring a bottle in position to be delivered to the label picking and carrying device, means for delivering a bottle from the conveyer into said label picking and carrying device and adjacent to a label thereon, a label affixing finger, means for moving the same into engagement with a label on the label picking and carrying device and to affix the same to a bottle thereon, a movable label wiper, means coating with said label affixing finger for holding said bottle stationary with relation to said label picking and carrying device and to said label wiper to allow said label picking and carrying device and said label wiper to move with respect to a bottle and to the label affixing finger to strip a label from the label picking and carrying device and wipe same on a bottle, and a conveyer for conveying a labeled bottle.

62. A bottle labeling machine including 65 a label picking and carrying device, a label box, means for moving the label picking and carrying device to the label box to pick a label therefrom, a paste supplying means, means for rotating said label picking and carrying device to gather a supply of paste from the paste supply means to carry a label into position to be affixed to a bottle, a conveyer for conveying bottles to be labeled, means for moving said conveyer to bring a

- bottle in position to be delivered to the label picking and carrying device, means for delivering a bottle from the conveyer into said label picking and carrying device 5 and adjacent a label thereon, a label affixing finger, means for moving the same into engagement with a label on the label picking and carrying device and to affix the same to a bottle thereon, a movable label wiper, means for coacting with said label affixing finger for holding said bottle stationary with relation to said label picking and carrying device and to said label wiper to allow said label picking and carrying device and 10 said label wiper to move with respect to a bottle and to the label affixing finger to strip a label from the label picking and carrying device and wipe same on a bottle.
63. A bottle labeling machine including a label picking and carrying device, a label box, means for moving the label picking and carrying device to the label box to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer to bring a bottle in position to be delivered to the label picking and carrying device, means for delivering a bottle from the conveyer into said label picking and carrying device and adjacent a label thereon, a label affixing finger, means for moving the same into engagement with a label on the label picking and carrying device and to affix the same to a bottle thereon, a movable label wiper, means for coacting with said label affixing finger for holding said bottle stationary with relation to said label picking and carrying device and to said label wiper to allow said label picking and carrying device and 15 said label wiper to move with respect to a bottle and to the label affixing finger to strip a label from the label picking and carrying device and wipe same on a bottle.
64. A bottle labeling machine including a label picking and carrying device, a label box, means for moving the label picking and carrying device to the label box to pick a label therefrom, a paste supplying means, means for rotating said label picking and carrying device to gather a supply of paste from the paste supplying means and to carry a label into position to be affixed to a bottle, a conveyer for conveying bottles to be labeled, means for moving said conveyer to bring a bottle in position to be delivered to the label picking and carrying device, means for delivering a bottle from the conveyer into said label picking and carrying device and adjacent a label thereon, a label affixing finger, means for moving the same into engagement with a label on the label picking and carrying device and to affix the same to a bottle thereon, a movable label wiper, means for coacting with said label affixing finger for holding said bottle stationary with relation to said label picking and carrying device and to said label wiper to allow said label picking and carrying device and 20 said label wiper to move with respect to a bottle and to the label affixing finger to strip a label from the label picking and carrying device and wipe same on a bottle.
65. A bottle labeling machine including a label picking and carrying device itself including a pair of oppositely positioned resiliently hinged label picking and carrying fingers, a label box, paste supplying means, means for rotating said label picking and carrying device on said paste supplying means to deposit a supply of paste on said label picking and carrying fingers, means for moving said label picking and carrying device vertically to bring one pair of said fingers into contact with a label in the label box to pick a label therefrom and to move said label picking and carrying device away from said label box in a straight line, means for rotating said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.
66. A bottle labeling machine including a label picking and carrying device itself including a pair of oppositely positioned hinged label picking and carrying fingers, a label box, paste supplying means, means for rotating said label picking and carrying device on said paste supplying means to deposit a supply of paste on said label picking and carrying fingers, means for moving said label picking and carrying device vertically to bring one pair of said fingers into contact with a label in the label box to pick a label therefrom and to move said label picking and carrying device away from said label box in a straight line, means for rotating said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.

a label on said fingers to be stripped therefrom upon movement thereof and means for wiping a label on a bottle.

67. A bottle labeling machine including a label picking and carrying device itself including a pair of oppositely positioned label picking and carrying fingers, a label box, paste supplying means, means for rotating said label picking and carrying device on said paste supplying means to deposit a supply of paste on said label picking and carrying fingers, means for moving said label picking and carrying device vertically to bring one pair of said fingers into contact with a label in the label box to pick a label therefrom and to move said label picking and carrying device away from said label box in a straight line, means for rotating said label picking and carrying device to bring one pair of said fingers with a label thereon into position to be applied to a bottle, means for conveying bottles to be labeled to said label picking and carrying device, means of affixing a label on said fingers to a bottle and for holding a bottle stationary with respect to said movable label picking and carrying device to cause a label on said fingers to be stripped therefrom upon movement thereof and means for wiping a label on a bottle.

68. A bottle labeling machine including a label picking and carrying device itself including a pair of oppositely positioned resiliently hinged label picking and carrying fingers, a label box, paste supplying means, means for rotating said label picking and carrying device on said paste supplying means to deposit a supply of paste on said label picking and carrying fingers, means for moving said label picking and carrying device to bring one pair of said fingers into contact with a label in the label box to pick a label therefrom and to move said label picking and carrying device away from said label box in a straight line, means for rotating said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.

69. A bottle labeling machine including a label picking and carrying device itself including a pair of oppositely positioned hinged label picking and carrying fingers, a label box, paste supplying means, means for rotating said label picking and carrying device on said paste picking and carrying fingers, means for moving said label picking

and carrying device to bring one pair of said fingers into contact with a label box to pick a label therefrom and to move said label picking and carrying device away from said label box in a straight line, means for rotating said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.

70. A bottle labeling machine including a label picking and carrying device itself including a pair of oppositely positioned label picking and carrying fingers, a label box, paste supplying means, means for rotating said label picking and carrying device on said paste supplying means to deposit a supply of paste on said label picking and carrying fingers, means for moving said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.

71. A bottle labeling machine including a label picking and carrying device itself including a pair of oppositely positioned resiliently hinged label picking and carrying fingers, a label box, paste supplying means, means for rotating said label picking and carrying device on said paste supplying means to deposit a supply of paste on said label picking and carrying fingers, means for moving said label picking and carrying device vertically to bring one pair of said fingers into contact with a label in the label box to pick a label therefrom and to move said label picking and carrying device away from said label box, means for rotating said label picking and carrying device to bring one pair of said fingers with a label thereon into position to be applied to a bottle, means for conveying bottles to be labeled to said label picking and carrying device, means for affixing a label on said fingers to a bottle on a bottle.

- a bottle and for holding a bottle stationary with respect to said movable label picking and carrying device to cause a label on said fingers to be stripped therefrom upon movement thereof and means for wiping a label on a bottle.
72. A bottle labeling machine including a label picking and carrying device itself including a pair of oppositely positioned hinged label picking and carrying fingers, a label box, paste supplying means, means for rotating said label picking and carrying device on said paste supplying means to deposit a supply of paste on said label picking and carrying fingers, means for moving said label picking and carrying device to bring one pair of said fingers into contact with a label in the label box to pick a label therefrom and to move said label picking and carrying device away from said label box, means for rotating said label picking and carrying device vertically to bring one pair of said fingers into contact with a label in the label box to pick a label therefrom and to move said label picking and carrying device away from said label box, means for rotating said label picking and carrying device to bring one pair of said fingers with a label thereon into position to be applied to a bottle, means for conveying bottles to be labeled to said label picking and carrying device to cause a label on said fingers to be stripped therefrom upon movement thereof and means for wiping a label on a bottle.
73. A bottle labeling machine including a label picking and carrying device itself including a pair of oppositely positioned label picking and carrying fingers, a label box, paste supplying means, means for rotating said label picking and carrying device on said paste supplying means to deposit a supply of paste on said label picking and carrying fingers, means for moving said label picking and carrying device vertically to bring one pair of said fingers into contact with a label in the label box to pick a label therefrom and to move said label picking and carrying device away from said label box, means for rotating said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.
74. A bottle labeling machine including a label picking and carrying device itself including a pair of oppositely positioned resiliently hinged label picking and carrying fingers, a label box, paste supplying means, means for rotating said label picking and carrying device to bring one pair of said fingers with a label thereon into position to be applied to a bottle, means for conveying bottles to be labeled to said label picking and carrying device to cause a label on said fingers to be stripped therefrom upon movement thereof and means for wiping a label on a bottle.
75. A bottle labeling machine including a label picking and carrying device itself including a pair of oppositely positioned hinged label picking and carrying fingers, a label box, paste supplying means, means for rotating said label picking and carrying device on said paste picking and carrying fingers, means for moving said label picking and carrying device to bring one pair of said fingers into contact with a label in the label box to pick a label therefrom and to move said label picking and carrying device away from said label box, means for rotating said label picking and carrying device to bring one pair of said fingers with a label thereon into position to be applied to a bottle, means for conveying bottles to be labeled to said label picking and carrying device, means for affixing a label on said fingers to a bottle and for holding a bottle stationary with respect to said movable label picking and carrying device to cause a label on said fingers to be stripped therefrom upon movement thereof and means for wiping a label on a bottle.
76. A bottle labeling machine including a label picking and carrying device itself including a pair of oppositely positioned label picking and carrying fingers, a label box, paste supplying means, means for rotating said label picking and carrying device on said paste supplying means to deposit a supply of paste on said label picking and carrying fingers, means for moving said label picking and carrying device to bring one pair of said fingers into contact with a label in the label box to pick a label therefrom and to move said label picking and carrying device away from said label box, means for rotating said label picking and carrying device to bring one pair of said fingers with a label thereon into position to be applied to a bottle, means for conveying bottles to be labeled to said label picking and carrying device to cause a label on said fingers to be stripped therefrom upon movement thereof and means for wiping a label on a bottle.

- device, means for affixing a label on said fingers to a bottle and for holding a bottle stationary with respect to said movable label picking and carrying device to cause a label on said fingers to be stripped therefrom upon movement thereof and means for wiping a label on a bottle.
77. A bottle labeling machine including a label picking and carrying device itself including a pair of hinged label picking and carrying fingers, means for supplying paste to said fingers, a label box, means for delivering a bottle on to said fingers, means for affixing a label carried by said fingers to a bottle thereon and for holding a bottle stationary relative thereto, means for moving said label picking and carrying device vertically to strip a label from said fingers and means for wiping a label on a bottle.
78. A bottle labeling machine including a label picking and carrying device itself including a pair of label picking and carrying fingers, means for supplying paste to said fingers, a label box, means for delivering a bottle on to said fingers, means for affixing a label carried by said fingers to a bottle thereon and for holding a bottle stationary relative thereto, means for moving said label picking and carrying device vertically to strip a label from said fingers and means for wiping a label on a bottle.
79. A bottle labeling machine including a label picking and carrying device itself including a pair of label picking and carrying fingers, means for supplying paste to said fingers, a label box, means for delivering a bottle on to said fingers, means for affixing a label carried by said fingers to a bottle thereon and for holding a bottle stationary relative thereto, means for moving said label picking and carrying device to strip a label from said fingers and means for wiping a label on a bottle.
80. A bottle labeling machine including vertically movable and rotatable label picking and carrying mechanism, a label box, means for supplying paste to said label picking and carrying mechanism, means for holding a bottle stationary with respect to said label picking and carrying mechanism,
- said bottle holding means including means for affixing a label to a bottle while said bottle is in a stationary position and means for wiping a label.
81. Bottle labeling mechanism including a label box, paste supplying means, label picking and carrying means for picking a label from the label box and carrying same into position to be applied to a bottle, means for affixing a label carried by said picking and carrying means to a bottle while in a stationary position, means for moving said picking and carrying means in a straight line with respect to a bottle to strip a label from said picking and carrying means, and to pick a label from the label box, means for wiping a label on a bottle and means for rotating said picking and carrying means to position a label for application to a bottle.
82. Bottle labeling mechanism including a label picker and carrier for picking a label, means for rotating the picker and carrier to position a label for application to a bottle, means stopping the rotation of the picker and carrier and means for affixing a label so positioned to a bottle while said label picker and carrier is in a stationary position.
83. Bottle labeling mechanism including a label picker and carrier, means for moving the same in a straight line to pick a label, means for rotating the picker and carrier, means for holding the label picker and carrier stationary to position a label for application to a bottle and means for affixing a label so positioned to a bottle.
84. Bottle labeling mechanism including a label picker and carrier, means for moving the same in a straight line to pick a label, means for rotating the label picker and carrier and means for holding the label picker and carrier stationary to position a label for application to a bottle.

In testimony whereof, I affix my signature, in presence of two witnesses. 95

JOHN J. GAYNOR.

Witnesses:

WETZEL SWARTZ,
MERLE IRICK.
